UNITED STATES PATENT OFFICE

90,519

DESIGN FOR A CHURCH

Rode N. Wall, Vancouver, British Columbia,
Canada

Application May 29, 1933. Serial No. 48,236

Term of patent 14 years

To all whom it may concern:

Be it known that I, RODE N. WALL, a citizen of Canada, residing at Vancouver, British Columbia, Canada, have invented a new, original, and ornamental Design for Churches, of which the following is a specification, reference being had to the accompanying drawings, forming a part thereof, wherein

Fig. 1 is a view in front elevation of a church showing my new design;

Fig. 2 is a perspective view of the same looking toward one side of the church; and

Fig. 3 is a perspective view taken from above the church and looking down on the same from a different angle.

I claim:—

The ornamental design for a church substantially as shown.

RODE N. WALL.
